UNITED STATES PATENT OFFICE.

DAISY ELLEN SMOOT, OF PIEDMONT, MISSOURI.

DEVICE FOR POISONING RODENTS.

1,019,543.

Specification of Letters Patent.

Patented Mar. 5, 1912.

Application filed June 29, 1911. Serial No. 635,997.

To all whom it may concern:

Be it known that I, DAISY ELLEN SMOOT, a citizen of the United States, residing at Piedmont, in the county of Wayne and State 5 of Missouri, have invented certain new and useful Improvements in Devices for Poisoning Rodents, of which the following is a specification.

This invention has for its object the provision of novel means for exterminating rodents by poison.

In carrying out the invention it is contemplated to provide a flat body composed, primarily, of layers of cardboard, straw-board, or the like, between which is interposed a poisonous substance, said body being intended to be tacked or otherwise secured over a rathole or other passage used by rodents.

20 The intent of the invention is to make the body of a material which may be readily gnawed through by rodents so that the latter will be poisoned and killed; the article being so constructed, that the poisonous 25 substance incorporated in the body is not exposed so as to give rise to likelihood of accidental poisoning of human beings or domestic animals through contact with the poisoning means described.

30 The invention is designed furthermore, in its preferred form, to afford special advantages from the standpoint of an article of manufacture, in that it may be constructed at a nominal cost, and a number of poisoning bodies or devices struck or cut from 35 a single blank of material.

With the above and other objects in view, a complete understanding of the invention will be accomplished by reference to the 40 following description, and accompanying drawings, in which:

Figure 1 is a sectional view showing the poisoning device secured over a partly closed opening such as are used by rodents. 45 Fig. 2 is a plan view of the device alone. Fig. 3 is a view showing a blank of material such as may be employed in making the poisoning devices. Fig. 4 is a view showing the invention in its commercial form.

50 In the following description and in the accompanying drawings similar reference characters refer to similar parts.

Describing the invention specifically, the numeral 1 denotes a floor or other body in 55 which is located an opening to form a rodent passage.

3 designates the poisoning device which consists of layers 3' and 3'', preferably of cardboard or other material through which a rodent can readily gnaw an opening. 60 The layers 3' and 3'' of the device 3 are preferably formed with register perforations or apertures 4, and between the said layers is interposed the poisonous substance 5 which may be a composition of Paris 65 green or other poisonous ingredients, susceptible of use for the purpose of the invention. The poisonous substance 5 is preferably applied to the lower layer 3'' of the device. And if the layers are of separate 70 pieces of material, the poisonous substance will be spaced from the edges of the layers as shown most clearly in the drawings. Furthermore, the poisonous substance will be spaced from the periphery of the single 75 opening in the device 3 formed by the apertures 4 of said layers. The poisonous substance 5 is therefore not exposed at any point of the device so that in the ordinary handling of the latter in commercial use 80 there is no likelihood of harmful results; the poisoning function of the device can not be accomplished in ordinary usage of the same except when the material from which the layers 3' and 3'' are made is gnawed 85 through, such operation being readily performed by the ordinary rodent, with disastrous results in the actual employment of the invention.

As shown in Fig. 3 it is preferred that the 90 poisoning devices herein described, be made from a single blank of material which is folded on a medial longitudinal line to provide at one end a closed edge, and to form the layers above mentioned, said layers are connected 95 together by an ordinary adhesive shown at 6, or any other means. The blank of material is folded on the medial line shown at 7 in Fig. 3, and it assumes the form shown in Fig. 4, and since the blank is perforated on the 100 lines shown at 8, the several devices formed in the above manner may be separated one from another and sold singly.

Having thus far described the invention, what is claimed as new is:

1. As a new article of manufacture, a poisoning device composed of layers of material connected at adjacent sides, the layers being formed with registering apertures providing an opening through the device, 110 and a poisonous substance interposed between said layers.

2. As a new article of manufacture, a poisoning device composed of superposed layers of material adhesively connected together, and a poisonous substance interposed between said layers, the poisonous substance as aforesaid being spaced from the edges of the layers and wholly inclosed by the latter, the layers being formed with registering apertures centrally thereto, forming an opening through the device, the poisonous substance being spaced from the edges of the apertures.

3. As a new article of manufacture, a rodent poisoning device made from a single blank of material folded upon itself to form layers, said layers being provided with registering apertures therein forming an open-

ing through the device, and a poisonous substance between said layers.

4. As a new article of manufacture, rodent poisoning means comprising a single blank of material folded upon itself to form layers, adhesive means connecting said layers, the folded blank having lines of perforations at intervals in its length dividing the same into a plurality of poisoning devices, and a poisonous substance interposed between said layers.

In testimony whereof I affix my signature in presence of two witnesses.

DAISY ELLEN SMOOT.
